CLAIM

The ornamental design for a speed drill, as shown and described.

DESCRIPTION

FIG. 1 is a right side perspective view of the speed drill of the present invention;

FIG. 2 is a right side elevational view thereof;

FIG. 3 is a left side elevational view thereof;

FIG. 4 is a front end view thereof;

FIG. 5 is a rear end view thereof.

FIG. 6 is a top view thereof; and,

FIG. 7 is a bottom view thereof.

The broken lines shown in FIGS. 1 and 2 are for illustrative purposes only and form no part of the claimed design.
